COMBINED COLLECTING AND MONEY CHANGING APPARATUS

Application filed October 2, 1928, Serial No. 309,861, and in Norway September 12, 1928.

The present invention has for its object a combined money changing and collecting automaton, which is particularly adapted for use on tramcars, omnibuses, railways and 5 similar means of transport, but which may also be adapted for use in other connections, such as for the sale of tickets and the like.

The object of the invention is to provide an apparatus into which the payer can drop 10 some coin corresponding to or larger than the amount which is to be paid, the apparatus being adapted to automatically upon the insertion of such a coin convey to a cash box the exact amount which should have been 15 paid, whereas the difference between the monetary value of the coin inserted and the said amount is automatically returned to the payer.

The coin inserted may be collected in a 20 separate cash box or in the same box as the amount to be paid (the fare).

In accordance with the problem to be solved, the characteristic feature of the present invention lies therein that any coin corresponding to a coin chute of the apparatus 25 is made to operate directly or indirectly a fare box containing coins or markers corresponding to the amount to be paid, whereas each of the said coin chutes at the same time 30 directly or indirectly serves to operate one or more coin boxes in accordance with the amount which is to be returned to the payer.

The effect of a coin inserted into the apparatus may consist in automatically starting 35 operating mechanisms by means of which the fare box as well as the return coin boxes are operated, or the effect may consist in releasing locking mechanisms or the like in order to enable the said coin boxes to be operated by hand.

As it will be easily understood, the apparatus may be combined with a coin sorting device in order that all coins may be inserted 45 into one slot, passing from there through a coin sorter of a conventional design, the said coin sorter delivering each separate coin to its respective chute.

On the drawings an embodiment of the invention is illustrated in connection with an

apparatus of the kind in which the several coin boxes are operated by hand.

Fig. 1 is a vertical section on the line I—I of Fig. 2, and Fig. 2 is a sectional plan on the line II—II of Fig. 1.

55

The apparatus illustrated on the drawings comprises three different coin chutes for coins of different sizes, one of these chutes being shown in cross section on Fig. 1.

The coin chute comprises a slot 2 adapted 60 for one particular size of coin, and the chute itself is pivotally mounted on the trunnion 3.

A spring 4 tends to maintain the pivoted coin chute in the position illustrated on Fig. 1. The apparatus further comprises a number of coin boxes in the form of tubular stacks, two of which, 5, 6, are illustrated on Fig. 1. These tubular stacks have their lower ends at a distance over the bottom plate 7 of the apparatus, corresponding approximately to the thickness of a coin 8.

On the bottom plate of the apparatus there are located slides 9, 10, 11 provided with openings which in the normal position of the slides lie directly below the several tubular 75 coin stacks, so that the lowest coin in each stack fits into an opening in the slide.

Springs 23, one of which is shown on Fig. 1, tend to maintain the slides in the normal position.

80

At the end of the slides which extends towards the pivoted coin chutes 1, there are located pivoted hooks 24, the distance between which is slightly shorter than the diameter of the coin for which the corresponding coin chute is adapted.

When a coin is let down through the chute as indicated in connection with coin 12 on Fig. 1, it will therefore be arrested between the pivoted hooks 24, whereas the upper part 90 of the coin still remains in the lower part of the chute. Consequently the coin in this manner forms a connection link between the pivoted coin chute and the corresponding slide 9, 10 or 11. By pressing against the upper part of the pivoted coin chute so as to 95 tilt the chute in the direction indicated by the arrow on Fig. 1, the lower part of the chute by means of the coin and the hooks 24 will pull the slide forwards as indicated by 100

the arrow on Fig. 2, thereby also moving the coins filling the opening of the said slide in a forward direction.

As it will be seen, this movement will bring the coin from the rear coin stack to an opening 13, through which it drops into the guide 14 and is let down in a cash box 15. The coin from the front coin stack is dropped through the opening 16 on to an incline 17 over which it is passed to the change pocket 18 which is accessible from the outside.

The coins in coin stack 6 are fare coins, i. e. they are either normal coins the value of which corresponds to the fare to be paid, or they are special fare marks or control marks adapted for the purpose. The guide 14 through which the fare coins are carried to the cash box 15 may if so desired also be connected by means of a special chute 19 with 20 a coin slot adapted for fare coins only.

When the slide 9 has been moved forwards a sufficient distance to let the coins from the coin stacks drop through their respective openings, arms 20 on the pivoted hooks 24 are engaged by stationary abutments 21, whereby the hooks are pivoted so as to let the coin resting between them slip through so as to pass into a coin guide 22, through which it is passed to a practical collecting box in accordance with the control system used.

In accordance with the embodiment illustrated on the drawings the apparatus is provided with three fare coin stacks 6, the coins from which are all passed through corresponding openings into the guide 14 from which they are passed to the cash box 15. Each of the said coin stacks 6 is actuated by one of the three slides illustrated so that the movement of any of these slides will have the 40 effect of transmitting a fare coin to the cash box 15.

As it will easily be understood, the apparatus might also have been provided with one fare coin stack 6 only, said fare coin stack 45 being then adapted to be actuated by all the slides of the apparatus.

This may for instance be effected by providing the fare coin stack in question with a special slide which is connected in such a 50 manner with the slides which are operated by means of the coin chutes, that it follows any of the last mentioned slides in their movement.

Besides actuating the fare coin stack 6, or 55 one of the fare coin stacks 6, each of the slides 9, 10, 11 actuates a number of coin stacks 5, the coins of which are carried to openings 16 from which they are passed along the incline 17 to the change pocket 18.

60 In accordance with the embodiment illustrated on the drawings the right hand coin chute (see Fig. 2) is adapted for a half-dollar. After this coin has been introduced, the pivoting of the coin chute will pass a fare 65 coin, for instance a marker having a nominal

value of 15 cents from the fare coin stack 6 to the cash box 15, whereas the four coin stacks 5 co-operating with the same slide will pass three ten-cent coins and one five-cent coin to the exchange pocket 18. In the case 70 of the middle coin chute which is adapted for a quarter, the effect with regard to the fare coin will be the same, whereas the two other coin stacks serve to return two five-cent coins to the payer (or one might use a single coin stack with ten-cent coins in this instance). In the case of the third coin chute which is adapted for twenty-cent coins, the same fare coin will be transmitted to the cash box, and 75 one five-cent coin to the payer. 80

Claim :

In an automatic fare collecting and money changing device having a casing and a plurality of coin chutes of different sizes for the insertion of coins and having a plurality of fare-representing check-holders for checks of different sizes; a slide below said fare-representing check-holders, a pair of hooks on one end of said slide below one of said coin chutes and adapted to engage an inserted coin, the coin-chute being pivoted to move said slide, a receptacle for collecting the inserted coins from said coin-chute, a receptacle for the collection of checks from said check-holder, the movement of the pivoted coin-chute feeding a check into said check collector, a cam on one side of each of said hooks, said cams being adapted to engage with said hooks to release the inserted coin from said hooks for depositing the coin in said inserted coin receptacle. 95

In testimony whereof we affix our signatures.

HJALMAR SAMUELSEN.
